UNITED STATES PATENT OFFICE.

FRANKLIN G. SLAGEL, OF BUFFALO, NEW YORK, ASSIGNOR TO FEEDERS MANUFACTURING COMPANY INC., OF BUFFALO, NEW YORK, A CORPORATION OF NEW YORK.

COOLING UNIT FOR REFRIGERATORS.

Application filed April 23, 1927. Serial No. 186,027.

This invention relates to a cooling unit for refrigerators which may be either submerged in brine for obtaining freezing temperatures as in ice cream cabinets, and the 5 same may also be used in commercial refrigerators in which a coating of ice accumulates on the unit.

It is the object of this invention to provide a cooling unit for this purpose which 10 is comparatively simple in construction, efficient in operation and very strong and compact so that it is not liable to be injured and will take up very little room.

In the accompanying drawings:

15 Figure 1 is a front elevation of the improved cooling unit. Figure 2 is a vertical transverse section of the same. Figure 3 is a side elevation thereof, partly broken away. Figure 4 is a top plan view partly broken 20 away.

Similar characters of reference indicate like parts in the several views of the drawings:

The numeral 10 represents the vaporizing 25 chamber, header or manifold which is adapted to receive the refrigerant in vaporized form and to deliver the same in liquid form in a well known manner. Below the vaporizing chamber are arranged a plurality 30 of tubular loops which communicate with the vaporizing chamber so as to receive refrigerant therefrom and absorb heat from the surrounding space.

In the preferred construction these loops 35 are arranged to form two longitudinal side rows and a single longitudinal central row arranged between the two side rows. Each loop of one of the side rows consists of inner and outer upright sections 11, 12 which 40 are arranged transversely in line relatively to the vaporizing chamber and having in-turned upper ends 13, 14, which are connected with the underside of the vaporizing chamber on one side thereof, and a return 45 bend or bow 15 connecting the lower ends of the upright sections 11, 12.

The longitudinal rows of the inner upright sections of both side rows are separated from each other by an intervening 50 space which receives the central row of intermediate loops, each of which consists of two upright sections 16, 17 arranged lengthwise in line and connected at their upper ends with the central part of the underside 55 of the vaporizing chamber while their lower

ends are connected by a return bend or bow 18.

The relative arrangement of the central and side rows of loops is such that upright sections or members of the central loops are 60 arranged transversely in line with or opposite to the spaces between the upright sections or members of the side loops, thereby distributing the radiating area of the cooling unit with greater uniformity over the 65 entire space in which the same is installed.

As an aid in increasing the heat absorption of the cooling unit a web 19 of sheet metal, preferably copper or the like, is arranged within each loop and each of the 70 webs is provided with horizontal corrugations 20 and vertical projections 21 on the several corrugations so as to secure the maximum radiating surface within a given 75 space.

By arranging the upright sections of each loop one behind the other crosswise of the cooling unit the spaces between the adjacent side loops will not become filled up by the 80 coating of ice which forms on the unit in case it is used in the cooling compartment of a refrigerator, but instead will form upright ribs of ice coating, as shown by dotted lines 22 in Fig. 4, thereby permitting of a considerable accumulation of ice on the unit 85 and avoiding obstructing the air spaces and permitting maintenance of free circulation of air and promoting rapid cooling of the space containing the cooling unit.

This unit not only effects a greater temperature transference but the same is also 90 very compact and this leaves more room available for storing goods to be cooled, and the same is also strong and durable and not liable to be injured when handling goods 95 stored in the cooling space near this unit.

Moreover, the several parts of this cooling unit can be manufactured economically and assembled very easily, thereby enabling 100 this unit to be marketed advantageously to the trade.

When using this unit in an ice-cream cabinet or the like as a substitute for an ice pack, the coils are submerged in a calcium chloride brine or other liquid refrigerant in 105 order to obtain zero temperature in which case no ice accumulates on the coils.

I claim as my invention:

1. A cooling unit for refrigerators comprising a vaporizing chamber, a plurality 110

of refrigerant loops arranged transversely relatively to said chamber and connected at their upper ends therewith, and a plurality of refrigerant loops arranged lengthwise relative to said chamber and connected at their upper ends therewith, each of said loops having two upright sections and the upright sections of said longitudinal loops being arranged opposite the spaces between the upright sections of the transverse loops.

2. A cooling unit for refrigerators comprising a vaporizing chamber, a plurality of longitudinal rows of transverse refrigerant loops connected at their upper ends with said chamber, and a row of longitudinal loops arranged lengthwise between said rows of transverse loops and connected at their upper ends with said chamber.

3. A cooling unit for refrigerators comprising a vaporizing chamber, a plurality of longitudinal rows of transverse refrigerant loops connected at their upper ends with said chamber, a row of longitudinal loops arranged lengthwise between said rows of transverse loops and connected at their upper ends with said chamber, each of said loops having upright sections and the upright sections of said longitudinal loops being arranged opposite the spaces between the upright sections of the transverse loops, and corrugated radiating webs arranged within each loop and connected at its edges with the members thereof.

In testimony whereof I hereby affix my signature.

FRANKLIN G. SLAGEL.
